METHOD OF CLEANING FEED
WATER HEATERSFrank H. Graham and Vern D. Washburn,
Jackson, Mich.No Drawing. Application April 14, 1932,
Serial No. 605,349

3 Claims. (Cl. 87—5)

This invention relates to an improved decarbonizing and degreasing composition and the method of using the same. In its broadest aspect, this invention has application in all fields 5 in which the removal of oils, greases and like foreign matter from surfaces is desired. More specifically considered, this invention has particular application in providing a decarbonizing composition which will readily remove the 10 gummy carbon which accumulates in locomotive feed water heaters resulting from the oil carried in the exhaust steam employed to heat the feed water.

It is a purpose of this invention to provide a 15 decarbonizing and degreasing composition which does not possess the undesirable features of known compositions employed for similar purposes, namely, low flash point and rapid evaporation, yet possesses a greater affinity for dissolving carbonized oils and greases than more 20 volatile solvents for oil and greases.

It is a further object of this invention to provide a decarbonizing and degreasing composition which is not appreciably affected in its action 25 by repeated use and may be readily reconditioned thus effecting decided economy in its employment.

Other objects and advantages of this invention will appear as the description of the invention 30 proceeds. It is to be distinctively understood, however, that we do not intend to limit ourselves to the exact details described but that we intend to include as a part of our invention, all such obvious changes and modifications of ingredients 35 as would occur to those skilled in this art and would fall within the scope of the claims.

In the preparation of our improved decarbonizing and degreasing composition, we employ a 40 light lubricating oil, constituting 60% to 85% of the volume, as a base. Any of the oils distilled off between and including gas oil and red engine oil has been found suitable to varying degrees. Such oils have a Saybolt viscosity at 45 100° F. of about 50 to 200 and a flash point of about 265° to 410° F. Preferably we employ a paraffine oil with a flash point of approximately 330° F. and of a viscosity of 80-85 at 100° F. To the paraffine oil base, 15% to 40%, by volume, of a mineral burning oil, preferably coal 50 oil, is thoroughly mixed.

Although our composition possesses satisfactory cleaning properties at normal atmospheric temperatures, we prefer to heat the same in a vat between 150° F. and 250° F. and immerge 55 the feed water heater or the like in the same.

To facilitate the decarbonizing and degreasing action of the composition, the vat may be equipped with an agitator. In operation, it has been found that a locomotive feed water heater, after a 75,000 mile run, literally clogged with a 5 gummy carbonized coating of oil and grease carried by the exhaust steam, may be completely cleaned in 15 to 30 minutes by soaking in a vat containing our improved composition.

In actual operation, an open vat containing 10 84 gallons of our improved composition has been in continuous operation for three weeks, cleaning large locomotive feed water heaters with less than 5% evaporation and no observable decrease of the effective cleaning properties. 15

From the foregoing description it will be apparent to those skilled in the art that we have provided a decarbonizing and degreasing composition which is particularly effective in cleaning locomotive feed water heaters and the like 20 having a high flash point and a low rate of evaporation.

Having thus described our invention, what we 25 claim as new and desire to protect by Letters Patent is:

1. The process of removing the gummy coating formed by the deposit of burned and carbonized lubricating oil from exhaust steam, resulting 30 from the high temperature of the exhaust steam in exhaust steam heated feed water heaters, and the like, which comprises immersing the heater in a composition comprising 60 to 85 percent paraffin oil distilled off directly above gas oil having a Saybolt viscosity at 100° F. of about 50 to 200 and a flash point of about 265° 35 F. to 410° F., and 15 to 40 percent coal oil at a temperature substantially between 150° F. and 250° F., said proportions being by volume.

2. The process of removing the gummy coating formed by the deposit of burned and carbonized lubricating oil from exhaust steam, resulting 40 from the high temperature of the exhaust steam in exhaust steam heated feed water heaters, and the like, which comprises immersing the heater in a composition comprising 60 to 85 percent paraffin oil distilled off directly above gas oil having a Saybolt viscosity at 100° F. of about 50 to 200 and a flash point of about 265° F. to 410° F., and 15 to 40 percent coal oil, and 45 agitating said composition at a temperature substantially between 150° and 250° F., said proportions being by volume.

3. The process of removing the gummy coating formed by the deposit of burned and carbonized 55

lubricating oil from exhaust steam, resulting from the high temperature of the exhaust steam in exhaust steam heated feed water heaters, and the like, which comprises immersing the heater

- 5 in a composition comprising 60 to 85 percent paraffin oil distilled off directly above gas oil

having a Saybolt viscosity at 100° F. of about 50 to 200 and a flash point of about 265° F. to 410° F., and 15 to 40 percent coal oil, said proportions being by volume.
